Primary Examiner — David Muller

(57) **CLAIM**

The ornamental design for an air sterilizing apparatus, as shown and described.

DESCRIPTION

FIG. 1 is a front perspective view of a first embodiment of my invention;

FIG. 2 is a front elevational view thereof;

FIG. 3 is a right side elevational view thereof, with the left side view being a mirror image of the right side;

FIG. 4 is a back elevational view thereof;

FIG. 5 is a rear perspective view thereof;

FIG. 6 is a top view thereof; and,

FIG. 7 is a bottom view thereof.

The broken line showing of parts of the drawings is included for the purpose of illustrating use and environment and forms no part of the claimed design.

1 Claim, 3 Drawing Sheets
